UNITED STATES PATENT OFFICE

JOSEPH FRASER, OF PARNELL, AUCKLAND, NEW ZEALAND

CARGO HOOK

Application filed January 20, 1932, Serial No. 587,823, and in New Zealand April 29, 1931.

This invention relates to hooks used in hoisting and lowering cargo and goods, out of and into ships' holds, and elsewhere, and has for its object the provision of an improved 5 form of hook of the type fitted with a guard or device designed to close the opening in the hook during the time cargo or goods is or are being hoisted or lowered.

The hook provided by this invention comprises a main portion and a guard pivoted thereto adapted to close on the point of said main portion, the latter being formed with a ratchet formation with which a spring 10 pressed pawl housed in the guard co-acts to 15 retain the guard in selected positions.

In order that the invention may be better understood, it will be further described with the aid of the accompanying drawing, wherein

20 Fig. 1 is a side elevation,
Fig. 2 an edge elevation, and
Fig. 3 a part sectional elevation (enlarged) 25 of the improved hook, while
Figs. 4 and 5 are part side elevations (with part of the locking mechanism housing removed) showing the guard in its closed and opened positions respectively.

Referring to the drawing, the improved hook comprises a main portion 1, and a guard 30 2 adapted to close the opening through which slings or the like are passed on to and removed from the hook, said guard 2 and main portion 1 being pivoted together by a bush 3 and pin 4 by means of which latter the hook is also attached to a shackle 5 or the like of the lifting apparatus.

The free or outer end of the guard 2 is recessed as at 6 or formed to pass upon a projection or rib 7 on the point or part 8 of the 40 main portion 1 of the hook on which it closes, and at its inner end said guard 2 contains a pawl 10 pivoted at 9 to the guard and shaped and normally pressed by a spring 11 also housed in the guard 2 to engage a selected recess 12 of a plurality thereof in the boss or rounded portion 1^a of the main portion of the hook, so as to retain the guard 2 in a desired position.

In order to enable the pawl 10 to be dis- 45 engaged from the recess 12 in which it may be

engaged, the said pawl is formed at each side with a bevelled hole or opening 10^a therein, so that it may be gripped between the thumb and forefinger, or be engaged by a suitable member to facilitate its operation against the 55 action of its spring 11.

The pawl 10 is completely housed in the guard 2, access being obtained thereto to operate same through openings 13 one in each side of the guard or pawl housing, said openings 13 being made large enough to permit of the pawl being given sufficient movement to be disengaged from the recess 12 in which it may be engaged.

With the guard 2 held open by the pawl 10 60 engaging in an appropriate recess 12 (Fig. 5), a sling or the like can be passed upon the hook, following which the guard 2 is merely pushed downwards to engage the point 8 and completely close the hook, the recesses 12 being of ratchet formation to enable this to be done. The recess 12 in which the pawl 10 engages when the guard 2 is down, provides a positive lock, which can only be removed by purposely operating the pawl 10 through the openings 13 and against the action of its spring 11 as before described, the sling or the like passed upon the hook 1 in the meantime being completely enclosed by the hook 1 and its guard or safety device 2. 65

The guard 2 is also fitted with a spring or spring pressed member 14 having a rounded outer end, and adapted when said guard is closed, to bear against the boss portion 1^a, where the radius of the latter increases, so as to give the guard 2 a slight tendency to move outwards, and so cause the pawl 10 to become positively locked in the lower ratchet recess 12, thereby ensuring positive locking of the 70 guard in its closed position.

In order to open the guard 2 it is necessary to first counteract the effect of the spring or spring pressed member 14 by using the heel of the hand as a fulcrum against the outer edge of the guard 2, while inserting the thumb and middle finger of the same hand through the openings 13 in opposite sides of the guard and using them to release the pawl 10 from the lower recess 12. This 75 80 85 90 95 100

operation is positive and depends upon the use of the heel of the hand combined with the use of the thumb and finger as aforesaid, the grip of the pawl 10 in the lower ratchet recess 12 being eased by the compression of the spring or spring pressed member 14 following which the pawl 10 can be easily disengaged from the lower recess 12 by the thumb and finger. It only requires the release of 10 the pawl 10 from the recess 12, and when this is done the guard 2 can be pushed full open or until the pawl 10 engages in the upper recess 12 in which latter position it is held by the spring 11. In order to relieve the 15 weight on the spring 11 when the guard 2 is in the open position, a small spring pressed ball catch can be provided in the guard 2 at 16 to bear against the boss portion 1^a and assist in retaining the guard open.

20 A screw 17 in the guard 2 at the back of the pawl 10 can be adjusted to prevent the latter from operating and so lock said pawl against operation when the guard 2 is closed, thus giving the hook the security of a shackle 25 should such be required.

What I do claim and desire to obtain by Letters Patent of the United States of America is:—

1. A device of the class described comprising a hook, said hook having a pair of recesses therein, each recess having a lower inclined wall and an upper abrupt wall, a guard pivotally connected with the hook, a spring-pressed pawl carried by the guard 30 and slideable on the inclined wall of the recesses and abutting the abrupt walls of the recesses in the hook to engage in one recess to hold the guard open, and in the other to hold the guard closed.
- 40 2. A device as claimed in claim 1 wherein the guard carries a spring-pressed member engageable with the hook and operating in opposition to the spring-pressed pawl, as and for the purpose set forth.
- 45 3. A device as claimed in claim 1, wherein adjustable means are carried by the guard and engageable with the pawl to hold the pawl positively engaged in the recess cooperative with the pawl for holding the 50 guard closed.

In testimony whereof he has affixed his signature.

JOSEPH FRASER.
